PRESSER ATTACHMENT FOR SHIRT FOLDING MACHINES

Wade W. Frost, Ailey, Ga., assignor to
David A. Freeman, Chicago, Ill.

Application April 9, 1958, Serial No. 727,443

6 Claims. (Cl. 223—52.1)

This invention relates to shirt folding machines and has more particular reference to a presser attachment for use with such machines for pressing the back outer side of the shirt collar during the collar forming process.

Machines employed by modern commercial laundries for shirt folding and collar forming usually comprise a table or support having a well-like collar receiving opening formed in its upper surface adjacent one end, and in which is mounted an expandable and contractible collar former assembly. The collar former assembly usually comprises three collar forming blocks, all made of metal and having a high degree of heat conductivity and carrying electrical heating elements. The foregoing construction permits placing the shirt face down on the support with the collar encircling the contracted collar forming blocks, then the blocks are expanded to engage the inner surface of the collar and are heated to form the collar. After the shirt has been properly folded, the heat is turned off, the collar forming blocks are contracted, and the finished shirt is removed from the table. In such apparatus, no provision is made for pressing the outer back side of the collar, which sometimes wrinkles during the collar forming process, and sometimes the collar slips off the blocks during the shirt folding process.

One object of the present invention is to provide a novel and improved presser attachment for shirt folding machines of the above type, which provides means for pressing the outer back side of the collar while engaged by the expanded collar forming blocks of the apparatus to press the fullness out of the collar, give an even crease around the collar, and prevent the collar from slipping off the blocks during the shirt folding process.

Another object of the present invention is to provide a presser attachment, as characterized above, in which a heated presser member is resiliently held against the back of the shirt collar during the collar forming process and is removed therefrom upon the completion of the collar forming process.

Another object of the present invention is to provide a presser attachment, as characterized above, wherein pneumatic means adapted to be connected to the pneumatic means for controlling the operation of the collar forming blocks are provided for controlling the operation of the heated presser member.

A further object of the present invention is to provide an attachment for use with shirt folding and collar forming apparatus which is simple and economical in construction, efficient in operation, and readily adapted to be mounted on the usual commercial shirt folding and collar forming apparatus used in modern commercial laundries.

Other objects and advantages of the invention will appear in the following specification when considered in connection with the accompanying drawings, wherein:

Fig. 1 is a perspective view showing a shirt folding

2

and collar forming machine having an attachment for pressing the outer back side of the collar, constructed in accordance with the present invention, mounted thereon;

Fig. 2 is a plan view of the attachment shown in Fig. 1; Fig. 3 is a side elevational view of the apparatus shown in Fig. 2;

Fig. 4 is a vertical sectional view taken on the line 4—4 of Fig. 2; and

Fig. 5 is a fragmentary plan view of the collar forming blocks shown in Fig. 1, and showing the manner in which the presser attachment of the present invention cooperates therewith.

The present invention provides a novel and improved presser attachment for shirt folding and collar forming machines and, in general, comprises a heatable presser member mounted on a supporting bracket adapted to be mounted on the shirt folding machine adjacent the collar forming blocks thereon, resilient means for moving the presser member into engagement with the outer back side of a shirt collar when mounted on the collar forming blocks of the shirt folding machine, and pneumatic means for normally holding the presser member in inoperative position.

Referring now to the drawings, there is illustrated in Fig. 1, a shirt folding machine, indicated generally at 10, having a presser attachment, indicated generally at 11, and constructed in accordance with the present invention, mounted thereon.

The shirt folding machine 11 may be of any suitable commercial type and, as shown, comprises a table or supporting member 12 having a generally flat shirt supporting surface 13 in which a well-like collar receiving recess 14 is formed adjacent one end; and a collar forming device, indicated generally at 15, mounted in the recess.

The collar forming device 15 may be of any suitable construction. Preferably, and as shown, it is of the general type such as shown in U.S. Patent No. 2,768,774, and comprises a fixed collar forming block 16 and two expandable and contractible collar forming blocks 17 and 18.

Any suitable means may be employed for expanding and contracting the movable collar forming blocks 17 and 18. Preferably, and in the particular machine shown, means generally similar to those shown in U.S. Patent No. 2,369,607, are employed. The blocks are expanded by spring pressure means (not shown) but are normally held in contracted position by means of a compressed air cylinder (not shown) having a piston stem connected to move the blocks to contracted position against the pressure of the spring. A control valve (not shown), operated by a hand lever 19 mounted on the table and connected to the valve, controls the admission of compressed air to and from the cylinder. Compressed air for operating the cylinder is supplied through a conduit 20 connected to the control valve and a suitable supply of compressed air. The collar forming blocks 16, 17 and 18 are heated electrically and the current to the blocks is controlled as by means of a selective heat control switch 21 mounted on the table adjacent the collar receiving opening.

The pressing attachment, as best shown in Figs. 2 and 3, comprises an elongated rod 22 mounted for sliding reciprocatory movement in a pair of spaced bearing members 23 and 24, suitably secured, as by welding, to one side of a support plate 25; a coil spring 26 mounted on the rod 22 between bearing member 24 and a square nut 27 adjustably mounted on the rod 22 for adjusting the tension of the coil spring; a heating member 28 carrying a pressing device 29 adjustably mounted on the inner end

of the rod 22; an air cylinder 30 mounted on the side of the support plate 25 opposite the rod 22 and having an extended piston stem 31 projecting from its rear end and engaging a stop member 32 adjustably mounted on the outer end portion of the rod 22; a flexible conduit 33 having one end connected to a control valve 34 mounted on the cylinder 30 for supplying compressed air to and from the cylinder; and a mounting plate 35 extending transversely of and fixedly secured to the plate 25, for mounting the attachment on a shirt folding machine.

The heating member 28 is shown as being in the form of a short section of piping having an electrical heating element 36 removably secured therein and connected to electrical wiring 37 adapted to be connected to a source of electric current to heat the heating element.

The pressing device 29 is shown as comprising an elongated flat strip of metal 38, preferably aluminum, and is secured as by screws, to a short metal strip 39 welded onto the heating elements 28.

The heating and presser devices are mounted on the inner end of the rod 22 for angular adjustment, as by means of a D-shaped clamp 40 having its bight 41 fixedly secured to the inner end of the rod 22, and with its jaws 42, 43 extending over and engaging the outer surface of the heating element 28. The jaws are held in tight clamping engagement with the heating element as by means of a bolt 44 extending through both jaws. By adjusting the nut 45 on one end of the bolt 44, the heating element can be angularly adjusted with respect to the longitudinal center line of the heating element so that the device may be used with various types of collar forming blocks.

The compressed air cylinder 30 is removably mounted on the support plate 25 as by means of bolts 46 passing through spacing blocks 47 and fastened in laterally extending ears 48 carried by a strap 49 extending partially around the cylinder and fixedly secured thereto as by welding.

The square nut 27 is slidably adjustably mounted on the rod 22 and is held in adjusted position thereon as by means of a set screw. In addition to providing means for adjusting the tension of the spring 26, the square nut, by engagement with the support plate 25, prevents any rotation of the rod 22.

The control valve 34, which may be of any suitable usual type, controls the rate of flow of compressed air to and from the compressed air cylinder, thereby giving control of the rate of reciprocating movement of the rod 22.

The attaching plate 35 provides means for removably securing the attachment to the shirt folding machine so that the rod 22 will be positioned to move the presser bar 38 into and out of engagement with the outer back side of a shirt collar when the shirt is placed on the folding machine with the collar encompassing the collar forming blocks (see Figs. 1 and 5).

From the foregoing, the operation of the pressing attachment is believed apparent. When employed with a shirt folding machine of the type shown in Fig. 1, the mounting plate 35 of the attachment is bolted to the table of the machine adjacent the collar forming blocks, in position for the reciprocating rod 22 to move the presser bar 38 into and out of engagement with the outer back side of a collar mounted on the collar forming blocks. When compressed air is admitted to the cylinder 30, the piston stem engaging the stop member 32 on the rod 22 will move the rod in a direction to retract the pressing device 29 on its inner end, thereby contracting the coil spring 26. When compressed air is exhausted from the cylinder 30, the spring 26 will move the rod 22 in a direction to bring the pressing device 29 into pressing engagement with the back outer side of the collar. The flexible air conduit 33 is connected to the air conduit leading from the control valve of the machine to the compressed air cylinder which operates to hold the collar forming blocks in contracted position, and the electric

wires 37 of the heating member 28 are connected to the selective control switch 21 on the shirt folding machine. When the attachment is thus mounted, no additional manipulations are required of the machine operator than are required when the machine is operated without the attachment. For example, when the lever 19 is turned to admit air to the compressed air cylinder of the machine to hold the collar forming blocks in contracted position, compressed air will be admitted to the compressed air cylinder 30 of the attachment to hold the presser member 38 in retracted position, and when the lever 19 is turned to exhaust air from the compressed air cylinder of the machine to permit the spring operated means to expand the collar forming blocks, compressed air will be exhausted from the compressed air cylinder 30 of the attachment to permit spring 26 to move the rod 22 to bring the presser member 38 into engagement with the outer back side of the collar on the collar forming blocks. In like manner, when the machine operates to turn the selective electric switch 21 to heat the collar forming blocks, the heating element 36 in the heating member 28 of the attachment will be heated.

While the pressing attachment has been described as employed with a shirt folding machine in which the collar formers are normally held in contracted position by compressed air devices, obviously, the attachment is equally adapted for use with shirt folding machines in which the collar formers are moved to contracted position and expanded position by mechanical means such as shown in Patent No. 2,768,774, in which case the flexible conduit for supplying and exhausting compressed air to the air cylinder 30 of the attachment would be connected to a two-way control valve for controlling the operation, and, while the heating member 28 has been shown as being heated electrically, obviously, it could be heated by any other suitable means.

From the foregoing, it readily will be seen that there has been provided a novel and improved presser attachment for a shirt folding machine of the type provided with a collar forming device for forming the collar while the shirt is being folded; an attachment which provides means for pressing the outer back side of the collar during the collar forming process and helps to hold the collar on the collar forming blocks while the shirt is being folded; an attachment which is simple in construction, easily adapted to various types of shirt folding machines, and efficient in carrying out its intended function.

Obviously, the invention is not restricted to the particular embodiment thereof herein shown and described.

What is claimed is:

1. A collar back pressing mechanism for cooperative assembly with a collar molding and shaping device having a plurality of molding and shaping blocks therein mounted for movement toward and away from each other between contracted and expanded positions to engage the inner surface of a garment collar to mold and shape the same, comprising a collar back pressing plate dimensioned and configured to press the back outer portion of a garment collar on the collar molding and shaping device, a slidably mounted member having an end thereof secured to said collar back pressing plate and carrying the same for reciprocating movement toward and away from the molding and shaping blocks in the collar molding and shaping device, and fluid pressure actuated mechanism connected to said slidably mounted member to move the same with said collar back pressing plate toward and away from the molding and shaping blocks in a path to which the paths of movement of said molding and shaping blocks are symmetrical.

2. A collar back pressing mechanism for cooperative assembly with a collar molding and shaping device having a plurality of molding and shaping blocks therein mounted for movement toward and away from each other between contracted and expanded positions to engage the inner surface of a garment collar to mold and shape the

same, comprising a collar back pressing plate dimensioned and configurated to press the back outer portion of a garment collar on the collar molding and shaping device, a slidably mounted member having an end thereof secured to said collar back pressing plate and carrying the same for reciprocating movement toward and away from the molding and shaping blocks in the collar molding and shaping device, selectively operable and controllable fluid pressure actuated mechanism connected to said slidably mounted member, and control means to control fluid pressure flow to said fluid pressure actuated mechanism to selectively permit said mechanism to move the slidably mounted member with said collar back pressing plate toward and away from the molding and shaping blocks in a path to which the paths of movement of said molding and shaping blocks are symmetrical.

3. A collar back pressing mechanism for cooperative assembly with a collar molding and shaping device having a plurality of molding and shaping blocks therein mounted for movement toward and away from each other between contracted and expanded positions to engage the inner surface of a garment collar to mold and shape the same, comprising a collar back pressing plate dimensioned and configurated to press the back outer portion of a garment collar on the collar molding and shaping device, a slidably mounted member having an end thereof secured to said collar back pressing plate and carrying the same for reciprocating movement toward and away from the molding and shaping blocks in the collar molding and shaping device, a fluid pressure actuated mechanism connected to said slidably mounted member, and means to interconnect said fluid pressure actuated mechanism and said collar molding and shaping device whereby said fluid pressure actuated mechanism is effective to move said slidably mounted member with said collar back pressing plate thereon toward and away from the molding and shaping blocks in coordination with movement of said molding and shaping blocks and in a path to which the paths of movement of said molding and shaping blocks are symmetrical.

4. A collar back pressing mechanism for cooperative assembly with a collar molding and shaping device having a plurality of molding and shaping blocks therein mounted for movement toward and away from each other between contracted and expanded positions to engage the inner surface of a garment collar to mold and shape the same, comprising a collar back pressing plate dimensioned and configurated to press the back outer portion of a garment collar on the collar molding and shaping device, heater means secured to said collar back pressing plate, a slidably mounted member having an end thereof secured to said collar back pressing plate and carrying the same for reciprocating movement toward and away from the molding and shaping blocks in the collar molding and shaping device, a fluid pressure actuated mechanism connected to said slidably mounted member, and means to interconnect said fluid pressure actuated mechanism and said collar molding and shaping device whereby said fluid pressure actuated mechanism is effective to move said slidably mounted member with said collar back pressing plate thereon toward and away from the molding and shaping blocks in coordination with

movement of said molding and shaping blocks and in a path to which the paths of movement of said molding and shaping blocks are symmetrical.

5. A collar back pressing mechanism for cooperative assembly with a collar molding and shaping device having a plurality of molding and shaping blocks therein mounted for movement toward and away from each other between contracted and expanded positions to engage the inner surface of a garment collar to mold and shape the same, comprising a mounting bracket, a pair of bearings secured to said mounting bracket and having aligned apertures therethrough, a slide rod mounted in said bearing members for reciprocable movement therein toward and away from the collar molding and shaping device in a path to which the paths of movement of the molding and shaping blocks in said molding and shaping device are symmetrical, a collar back pressing plate mounted on an end of said slide rod at the end thereof adjacent to said collar molding and shaping device, a fixed stop member secured to said rod between said bearings, a spring tensioned between one of said bearings and said fixed stop member, and fluid actuating means mounted on said mounting bracket and connected to said slide rod to move the same with said collar back pressing device in one direction against the force of said spring and in an opposite direction in the direction of the force of said spring, toward and away from the molding and shaping blocks.

6. A collar back pressing mechanism for cooperative assembly with a collar molding and shaping device having a plurality of molding and shaping blocks therein mounted for movement toward and away from each other between contracted and expanded positions to engage the inner surface of a garment collar to mold and shape the same, comprising a mounting bracket, a pair of bearings secured to said mounting bracket and having aligned apertures therethrough, a slide rod mounted in said bearing members for reciprocable movement therein toward and away from the collar molding and shaping device in a path to which the paths of movement of the molding and shaping blocks in said molding and shaping device are symmetrical, a collar back pressing plate mounted on an end of said slide rod at the end thereof adjacent to said collar molding and shaping device, a fixed stop member secured to said rod between said bearings, a spring tensioned between one of said bearings and said fixed stop member, fluid actuating means mounted on said mounting bracket and connected to said slide rod to move the same with said collar back pressing device in one direction against the force of said spring and in an opposite direction in the direction of the force of said spring, toward and away from the molding and shaping blocks, and selective controllable valve means to control fluid pressure flow to said fluid pressure actuated mechanism to selectively control operation of said collar back pressing mechanism.
